Patented July 1, 1958

183,116

LOUVERED PANEL

Rudy P. Capranica, Arcadia, Calif.

Application March 2, 1956, Serial No. 40,438

Term of patent 14 years

(Cl. D62—4)

FIG. 1.

FIG. 2.

FIG. 3.

FIG. 4.

FIG. 5.

Fig. 1 is a view in front elevation of a louvered panel showing my new design;

Fig. 2 is a rear elevation of same;

Fig. 3 is an enlarged top plan view of the louvered panel shown in Fig. 1;

Fig. 4 is a view in cross section of the louvered panel as seen on the line 4—4 of Fig. 3; and

Fig. 5 is a fragmentary detail view of the lower louver element in Fig. 1.

The characteristic features of my design for the louvered panel disclosed resides in the longitudinal and transverse arcuate curvature of each louver coupled with concave curvatures at the ends of the louvers and the formation of the arcuate marginal portions of each of the louvers with a downwardly and inwardly turned substantially flat facet.

I claim:

The ornamental design for a louvered panel, substantially as shown and described.
